UNITED STATES PATENT OFFICE.

GEORGE E. HAMILTON, OF JACKSONVILLE, FLORIDA.

LUBRICATING SYSTEM FOR INTERNAL-COMBUSTION ENGINES.

Application filed February 21, 1924. Serial No. 694,339.

To all whom it may concern:

Be it known that I, GEORGE E. HAMILTON, a citizen of the United States, residing at Jacksonville, in the county of Duval and State of Florida, have invented certain new and useful Improvements in Lubricating Systems for Internal-Combustion Engines; and I do hereby declare the following to be a full, clear, and exact description of the invention, such as will enable others skilled in the art to which it appertains to make and use the same.

This invention relates to improvements in lubricating systems for internal combustion engines, and particularly to the lubricating system of engines of that type employing a fly-wheel magneto.

The primary object of the invention is the provision of novel means by which a constant circulation of the greater portion of the oil in the system may be maintained through the crank case of the engine, and by which the quantity of lubricant in the system may be determined by the operator 25 of the automobile without leaving his seat.

A further object of the invention is the provision of means by which the stated object may be obtained, which shall be simple, durable and efficient, and which may be readily and quickly applied to the engine.

With the above and other objects in view, the invention consists in the construction, combination and arrangement of parts hereinafter fully described and claimed, and illustrated in the accompanying drawings, wherein:

Figure 1 is a view in side elevation of an internal combustion engine equipped with a lubricating system constructed in accordance with my invention,

Figure 2 is a sectional view taken on the plane indicated by the line 2—2 of Figure 1, looking in the direction indicated by the arrows,

Figure 3 is a sectional view taken on the plane indicated by the line 3—3 of Figure 1, looking in the direction indicated by the arrows,

Figure 4 is a sectional view taken on the plane indicated by the line 4—4 of Figure 3, looking in the direction indicated by the arrows,

Figure 5 is a vertical sectional view through the breather pipe, illustrating the

manner in which the discharge end of the 55 circulating pipe enters the breather pipe.

Figure 6 is a detail view in side elevation of the cut off valve in the circulating pipe, illustrating particularly the connection between the control rod and the plug of the 60 valve, and

Figure 7 is a vertical sectional view of the sight feed apparatus.

Referring to the drawings by reference numerals, 1 designates an internal combustion engine of that type employing a fly-wheel magneto. The engine embodies a crank case 2, a fly-wheel housing 3, a crank shaft 4, a fly-wheel 5 secured to the crank shaft, and magnets 6 secured to the fly-wheel.

In engines of this type, the oil flows from the crank case 2 to the fly-wheel housing 3, and in order to prevent the accumulation 75 of more than a predetermined quantity of oil in the fly-wheel housing I employ means for conveying the oil from the bottom of the fly-wheel housing to the forward end of the crank case. This means comprises a

curved tube 7 which at its lower end is in communication with the bottom of the fly-wheel housing 3 and which at its upper end is in communication with a tube 8 which discharges into the breather pipe 9 of the engine. A T-coupling 10 connects the discharge end of the tube 7 with the intake end of the tube 8, and also connects the discharge end of the tube 7 with a tube 11 which discharges at its upper end into a sight feed apparatus 12. The discharge end of the tube 8 passes into the breather pipe 9 in the manner illustrated in Figure 5, and the down-turned end 8a of the tube prevents the tube from being accidentally detached from the breather pipe.

The oil in the fly-wheel housing 3 is kept in constant motion during the operation of the engine by the fly-wheel 5 and the magnets 6 carried thereby. An oil dip or intake member 13 is connected to the intake end of the tube 7 by a coupling 14, and it is threaded into the drain opening 15 in the bottom of the fly-wheel housing 3. The upper end of the dip or intake member 13 extends for

100 a considerable distance into the fly-wheel housing 3; it is enlarged laterally as shown in Figure 4, and is provided with a side opening 16 through which the oil is forced

under such pressure as to flow upwardly through the tube 7 and thence forwardly through the tube 8 into the forward end of the crank case 2, and owing thereto a constant circulation of oil through the crank case and fly-wheel housing will be maintained. The tube 7 is curved to conform to the configuration of the fly-wheel housing 3 and extends from the bottom of the housing 10 to a point above the crank case 2. The tube 8 extends forwardly from the discharge end of the tube 7 to the breather pipe 9 as clearly shown in Figures 1 and 2. In order to insure the return of the oil to the forward 15 end of the crank case 2 when the engine is idling or when the quantity of oil in the system is low, an auxiliary connection is established between the interior of the fly-wheel housing 3 and the tube 7 by means 20 of a tube 17 which is connected to the tube 7 by means of a coupling 18 and which is connected with the interior of the fly-wheel housing 3 by means of an elbow 19. To insure the passage of oil into the upper 25 open end of the elbow an oil deflecting plate 20 is secured within the fly-wheel housing 3 as shown in Figures 3 and 4. The tube 17 is equipped with a cut-off valve 21 which is opened whenever the flow of oil through 30 the dip or intake member 13, the tube 7 and the tube 8 falls below the maximum carrying capacity of these parts.

The sight feed apparatus 12 comprises a casing 22, a glass panel 23, a float 24 and 35 a float rod 25. Under normal conditions, that is when there is no oil in the casing 22, the lower end of the rod 25 rests upon the bottom wall of the casing 22. The upper end of the rod 25 passes through the upper side 40 of the lateral wall of the casing 22 and through a guide 26. The opening 27 through which the upper end of the rod 25 passes vents the casing 22, and the rod is provided with a conical portion 28 which closes the 45 opening when a predetermined quantity of oil accumulates in the casing 22. The float 24 is threaded upon the rod 25 to permit it to be adjusted to any point in the length of the rod. Under normal conditions, the oil 50 will not flow through the pipe 11 into the sight feed apparatus 12, and when it is desired to determine the quantity of oil in the system the valve 29 in the pipe 8 is closed; and this may be done through the medium 55 of a rod 30 which is connected to the stem 31 of the valve 29 by a universal coupling 32. The rod 30 extends upwardly and rearwardly from the valve 29 to a point within convenient reach of the operator of the automobile, and this end is provided with a handle 33, as shown in dotted lines in Figure 1 and full line in Figure 2. The sight feed apparatus is preferably secured to the instrument board of the automobile. The quantity 60 of oil in the system is determined from the

speed at which the engine must be operated to force the oil through the tubes 7, 8 and 11 into the casing 2 when the valve 29 is closed. When the quantity of oil in the system is low, the engine will have to be operated at a high rate of speed in order to cause the oil to flow to the sight feed apparatus. When there is sufficient oil in the system to insure the proper lubrication of the engine parts, the oil will flow into the sight feed apparatus when the engine is operating at a low rate of speed. It has been observed that when the oil is very low in the system, it bubbles and foams on reaching the sight feed apparatus. The valve 28 prevents the escape of oil through the opening 27 in the sight feed apparatus, and the opening permits the oil to quickly flow back into the system on the opening of the valve 29. Due to the plate 20, which together with the adjacent lower portion of the fly-wheel housing 3 forms a pocket into which the oil is forced by the rotation of the fly-wheel 5 and the magnets 6 and with which the elbow 19 communicated, the oil is forced through the elbow under a greater pressure than it is forced through the intake member 13, and owing thereto a circulation of the oil through the system may be maintained when the oil in the system is low and when the engine is idling.

It should be understood that the drawings are merely illustrative and do not give the exact proportions. Furthermore, the said drawings are illustrative of a preferred construction, it being my expectation that various changes and modifications may be made without departing from the spirit and scope of my invention.

What is claimed is:

1. An internal combustion engine having a crank case, a fly-wheel, a housing for the fly-wheel at the rear end of and communicating with the crank case, an oil intake member communicating with the bottom of the housing, a tube extending upwardly from the intake member to a point above the crank case, a breather pipe communicating with the front end of the crank case, and a second tube extending from the upper end of the first tube to the breather pipe and having its front end down-turned and entering the breather pipe.

2. An internal combustion engine having a crank case, a fly-wheel housing at the rear end of and communicating with the crank case, tubes communicating with the lower side of the housing at relatively spaced points, a plate within the housing over the intake of one of said tubes, a valve located in said last named tube, and a third tube communicating with said first named tubes and with the front end of the crank case.

3. An internal combustion engine having a crank case, a fly-wheel, a housing for the

fly-wheel communicating with one end of the crank case, oil intake members communicating with the housing, a tube extending from one of said intake members to the other end of the crank case, a second tube extending from the other of said intake members to the first tube, and a valve in said second tube.

In testimony whereof I affix my signature in presence of two witnesses.

GEORGE E. HAMILTON.

Witnesses:

Mrs. A. M. ELDER,
Wm. WHITMORE.
